UNITED STATES PATENT OFFICE.

EDWARD F. GEHRKENS, OF SCHENECTADY, NEW YORK, ASSIGNOR TO
GENERAL ELECTRIC COMPANY, A CORPORATION OF NEW YORK.

SWITCHING DEVICE.

No. 848,893.

Specification of Letters Patent.

Patented April 2, 1907.

Application filed October 22, 1904. Serial No. 229,537.

To all whom it may concern:

Be it known that I, EDWARD F. GEHRKENS, a citizen of the United States, residing at Schenectady, county of Schenectady, State 5 of New York, have invented certain new and useful Improvements in Switching Devices, of which the following is a specification.

In alternating-current systems it is often necessary to vary the voltage supplied to the 10 distributing-mains through a wide range, and it is customary to produce this effect by providing a transformer having a plurality of taps and a movable contact device, such as a dial-switch blade connected to one side of the distributing-circuit and movable from one tap to another to vary the number of effective turns of the transformer. As it is often undesirable to open the distributing-circuit while changing from one tap to the next it is 15 customary to make the dial-blade wide enough to bridge the space between two taps, and thus effect the change from one tap to the next without actually opening the distributing-circuit. This arrangement has 20 the disadvantage, however, of momentarily short-circuiting the transformer-turns between the two taps, and, furthermore, is likely to produce excessive sparking at the 25 dial-contacts.

This invention involves an improved means for regulating the pressure of an alternating-current circuit by varying the number of effective turns of a transformer without interrupting the line-current and without short-circuiting the transformer-windings. The device comprises two separate dial-switches having contact-blades connected together through a reactive coil the center of which is connected to one side of the line. In circuit 30 with each dial or contact blade is an automatic circuit-breaker which opens the circuit before the blade leaves a dial-contact, so that heavy current is never opened on the dial. The dial-blades operate successively, one 35 blade always making contact with a transformer-tap and carrying all the load until the other blade has reached the next tap. The current in the distributing-main is therefore never broken and remains practically undisturbed except for the change in pressure effected by the change from tap to tap.

Figure 1 is a diagrammatical representation of the electrical features of my invention. Fig. 2 is an elevation of a quick-break or

auxiliary switch. Fig. 3 is a side elevation of 55 the two dial-switches. Fig. 4 is an elevation of the main switch. Fig. 5 is a detail view of the auxiliary switch.

In Fig. 1 the transformer-coil 1 is supplied by power from any suitable source, and the 60 coil 2 supplies current to the distributing-mains 3 and 3'. A plurality of taps 4 4' 4² for the transformer-coil 2 are connected to the dial-contacts 5 5' 5², &c., of the main dial-switch (shown in Fig. 4) and also to the dial-contacts 6 6' 6² of the auxiliary dial-switch, 65 (shown in Figs. 2 and 5,) each transformer-tap being connected to one contact of each dial-switch. A dial-blade 7 is adapted to move over the dial-contacts 5; 5', and 5² and an auxiliary dial-blade 8 is adapted to move over the dial-contacts 6, 6', and 6².

The conductors leading from the dial-blades 7 and 8 are connected to the distributing-main 3 through the reactance-coil 9 and 70 are provided, respectively, with automatic circuit-breakers 10 and 11.

Contact-blade 7 is provided at its lower end with a conducting-arm 12, insulated from the other parts of dial-blade 7 and adapted to 75 make electrical contact between a conductor 13 and the contact-points 14, 14', and 14². These latter contact-points are so arranged that whenever the dial-blade 7 moves from one tap to the next the circuit-breaker 10 80 will open before the blade leaves one dial-contact and will remain open until the dial-blade establishes a good contact with the next tap.

The energizing-coil 15 of circuit-breaker 10 is connected directly across the distributing-mains 3 and 3', except for the gap between the conductor 13 and the contact-points 14, 14', and 14². Assuming that it is necessary to change from tap 4 to tap 4', the 85 operation of the switches is as follows: The 90 dial-blade 7 is moved gradually to the right until it is partially out of contact with dial-contact 5, in which condition the lower part 12 of the blade completes the circuit through the energizing-coil 15 and opens the circuit-breaker 10, thus allowing the entire line-current to be carried by the other dial-blade 8. The circuit-breaker coil 15 remains energized until the blade 7 is in contact with the dial-contact 5' for a certain portion of its width, 95 whereupon the circuit between the contact-point 14 and the conductor 13 is broken, and the circuit-breaker 10 closes the circuit be- 100 105

between the main line 3 and the dial-blade 7 and energizes the coil 16 of circuit-breaker 11 by allowing current to pass from one dial-blade to the other through the movable part 5 of the circuit-breaker 10. For the instant during which both circuit-breakers are closed and the two contact-blades are connected to different taps the reactance 9 serves to prevent excessive flow of current 10 through the short-circuited turns of the transformer-coil 2. Immediately after circuit-breaker 11 has opened, thus relieving the auxiliary blade 8 from the flow of line-current, the mechanical arrangement of the 15 snap-switch, hereinafter described, throws the dial-blade 8 to the next contact 8', thus de-energizing the circuit-breaker coil 16 and allowing circuit-breaker 11 to close, thus permitting a proper division of the line-current 20 between the two dial-blades 7 and 8. The currents flowing from the two blades through the reactive coil 9 to the line conductor 3 neutralize each other, so that under normal working condition this coil exerts no sub- 25stantial impedance to the flow of line-current.

Fig. 4 shows the main dial-blade 7 and the contacts 5, 5', and 5'', also the conductor 13, arranged in segmental form and adapted to 30 be connected with the contact-points 14, 14', and 14'' by the conducting-arm 12 of the switch. A uniform movement of rotation may be imparted to the blade 7 by means of the hand-wheel 17, connected thereto through 35 the worm-gear 18 and to the shaft 19, on which the blade 7 is rigidly mounted. The auxiliary or quick-break dial-switch (shown in Figs. 2 and 5) comprises the arm 20 and the dial-blade 8. The former is rigidly connected to the shaft 19, and thus turns simultaneously with the dial-blade 7, while the latter has an intermittent snapping motion produced by the mechanism shown in detail in Fig. 6. The uniformly-rotating arm 20 has 45 two movable wings 21 and 22, pivotally connected thereto by the pivots 23 and 24 and normally held against the sides of the arm 20 by the coil-spring 25. The snapping dial-blade 8, which is located back of the arm 20, carries at its lower end two dogs 27 and 28, pivotally supported thereto and normally held in engagement with the rack 29 by the coil-spring 30. The lower end of the arm 20 is provided with a fan-shaped projection 31, 55 on the rear surface of which are located the cam-surfaces 32 and 33, which serve to disengage the dogs 27 and 28 from the teeth of the rack 29. In Fig. 5 the arm 20 has rotated until the dial-blade 8 is just at the 60 point of snapping to the next dial-contact. A slight additional movement of the arm 20 would cause the cam-surface 32 to lift the dog 27 from the corner of the teeth with which it engages, and the spring 26 would 65 cause an elevation of the lower end of the

arm 20 and blade 8, thus snapping the upper end of blade 8 to the next dial-contact. This effect is produced by the compressing movement exerted on the edges of the two arms 8 and 20 through the medium of the wings 21 and 22, as the contact-surfaces 24' and 22'' on the inner edges of these wings are broad enough to engage the edges of both arms 20 and 8. By properly locating the cam-surfaces 32 and 33 this snapping action may be secured at any predetermined angular displacement between the arms 20 and 8, and consequently at a similar angular displacement between the arm 8 and the arm 7. If the dial-blade 8 should accidentally stick to any one of the dial-contacts, the continued movement of the hand-wheel 17 would force the upper edge 35 of the wing 21 against the side of the rotating arm 20, and any continued movement of the hand-wheel would operate directly on the dial-blades through the medium of the bearing-surface 21' at the lower end of the wing 21 and forcibly move the blade 8 to the next dial-contact.

As previously stated, the contact-blades 7 and 8 are out of circuit when passing from one tap to the next, so that heavy currents are never broken at the dial-contacts and the life of the dials is thus greatly increased. Furthermore, by the use of my invention I am able to successfully regulate circuits carrying heavy currents even when the voltage between successive transformer-taps is comparatively high.

What I claim as new, and desire to secure by Letters Patent of the United States, is—

1. The combination of a distributing-circuit, a transformer having a plurality of taps, said transformer connected to one side of said circuit, a contact-blade connecting the other side of said circuit to one of said taps, means for moving said contact-blade from tap to tap, and a circuit-breaker for interrupting the current through said blade during said movement from tap to tap.

2. The combination of a distributing-circuit, a transformer having a plurality of taps, said transformer connected to one side of said circuit, a plurality of contact-blades connecting the other side of said circuit to one of said taps, means for successively moving said blades from tap to tap, and means for interrupting the current through one of said blades during its movement from tap to tap.

3. In an electrical system, the combination of distributing-circuits, a source of current connected to one of said means, a plurality of taps for said source of current, a plurality of contact-blades connecting one of said means to said source of current, means for successively moving said contact-blade from tap to tap, and automatic means for interrupting the current through one of said blades during its movement from tap to tap.

4. The combination with a source of cur-

rent having a plurality of taps, of a main contact-blade in circuit with one of said taps, means for moving said blade from tap to tap, an auxiliary contact-blade connected through an impedance to said main contact-blade, and means for imparting to said auxiliary blade an intermittent motion with respect to said main contact-blade.

5. In an electrical system, the combination of a transformer having a plurality of taps, a distributing-main, a contact-blade connecting said distributing-main to one of said taps, an auxiliary blade, a reactance device connected between said blades, means for moving said first-named blade from tap to tap, and an automatic circuit-breaker for interrupting the current through said first-named blade during its movement from tap to tap.

6. The combination with a transformer having a plurality of taps, of a main contact-blade in circuit with one of said taps, means for moving said blade to a second tap, means for opening the circuit through said blade before it leaves said first-named tap, means for closing said circuit when said blade is in contact with said second-named tap, an auxiliary contact-blade, and means for imparting to said auxiliary blade an intermittent motion with respect to said main contact-blade.

30. 7. The combination with a source of current having a plurality of taps, of a main contact-blade in circuit with one of said taps, means for moving said blade from tap to tap, an auxiliary contact-blade, means for imparting to said auxiliary blade an intermittent motion with respect to said main contact-blade, a reactance device connected between said blades and a distributing-circuit con-

nected to said reactance device and to said source of current.

8. The combination with a transformer having a plurality of taps, of a main contact-blade in circuit with one of said taps, means for moving said blade from tap to tap, an auxiliary contact-blade, means for imparting to said auxiliary blade an intermittent motion with respect to said main contact-blade, a reactance device connected between said contact-blades, and automatic means for alternately disconnecting said contact-blades from said reactance device during said movement from tap to tap.

9. The combination with distributing-mains of a transformer having a plurality of taps, a main contact-blade in circuit with one of said mains, an auxiliary contact-blade in circuit with said main, means for moving said blades from tap to tap, and automatic means for alternately disconnecting said contact-blades from said main during said movement from tap to tap.

10. The combination with a transformer having a plurality of taps, of a main contact-blade and an auxiliary contact-blade in circuit with one of said taps, a reactance device connected between said blades, means for moving said blades from tap to tap, and automatic means for alternately disconnecting said contact-blades from said reactance device during said movement from tap to tap.

In witness whereof I have hereunto set my hand this 20th day of October, 1904.

EDWARD F. GEHRKENS.
